ACTIVATED TOY BIRD

William Eugene Polk, New York, N. Y.

Application May 6, 1953, Serial No. 353,334

5 Claims. (Cl. 46—124)

This invention relates to toys of the type wherein an object, such as a bird or animal is suspended between spring arms and mounted whereby contracting and expanding movements of the arms cause an object to move upwardly and downwardly representing a bird in flight. 15

The purpose of this invention is to provide a spring actuated toy adapted to be operated with one hand wherein an object suspended between elements of the toy may be moved vertically with the length of travel controlled by the hand of the operator. 20

Various types of objects have been suspended by rubber bands and other elements between arms urged outwardly by spring inherent in the arms, however, rubber bands, or similar elements provide comparatively loose connections and it is difficult to control the movement of the object. With this thought in mind this invention contemplates an object suspended between spring arms with parts of the object hinged to the arms and also hinged to the body of the object and wherein the movement of the object is controlled by spring elements. 25

The object of this invention is to provide an activated toy of the type having wings hinged to a body wherein the wings are urged toward extended positions by spring action inherent in the arms and to positions above and below the arms by an additional spring member. 30

Another object of the invention is to provide an activated toy of the type having a body suspended between spring actuated arms in which positive connections are provided between the arms and toy. 35

A further object of the invention is to provide an activated toy including combinations of spring elements for controlling movements of a body between arms, in which the toy is of a simple and economical construction. 40

With these and other objects and advantages in view the invention embodies a body having wings hinged to the sides thereof with arms of resilient material hinged to the wings and with the position of the body in relation to the arms controlled by a spring. 45

Other features and advantages of the invention will appear from the following description taken in connection with the drawings, wherein:

Figure 1 is a view looking upwardly toward the under side of the toy illustrating the toy with the wings extended and with bearing elements on the wings shown in section.

Figure 2 is a plan view of the toy shown in Fig. 1 with the arms contracted and with part of one of the wings broken away and shown in section.

Figure 3 is a cross section through the toy taken on line 3—3 of Fig. 1 showing the toy with the wings extended.

Figure 4 is a cross section, similar to that shown in Fig. 3 showing the toy with the wings contracted.

Figure 5 is a plan view similar to that shown in Fig. 2 with parts of the body broken away and shown in section and illustrating a modification wherein springs are incorporated in the hinges connecting the wings to the body.

2

Figure 6 is a cross section taken on line 6—6 of Fig. 5, with the parts shown on an enlarged scale also illustrating the springs in the hinges connecting the wings to the body.

5 Figure 7 is a plan view, similar to that shown in Fig. 2 illustrating a further modification wherein the wings are suspended from the body with flat spring elements.

Figure 8 is a cross section taken on line 8—8 of Fig. 7 also showing the wings connected to the body with flat spring elements and with parts of the wings broken away. 10

Figure 9 is a plan view similar to that shown in Fig. 2 illustrating a further modification wherein the wings are hinged on spring arms and the body is carried by a spring actuated bar.

Figure 10 is a side elevational view showing the device as shown in Fig. 9 with part of one of the wings broken away and showing the spring elements contracted.

Figure 11 is a side elevational view similar to that shown in Fig. 10 illustrating the positions of the parts with the mounting elements expanded vertically and with part of one of the wings broken away.

Figure 12 is a cross section taken on line 12—12 of Fig. 9 showing the wings contracted, with the body moved upwardly.

Figure 13 is a similar section illustrating the positions of the parts with the body moved downwardly.

Figure 14 is a perspective view showing the spring arms of Figs. 9 and 10 and illustrating a further modification wherein the arms are carried by a spring element.

Referring now to the drawings wherein like reference characters denote corresponding parts the improved activated toy of this invention includes a body 10 having wings 11 and 12 hinged to the sides with the wings hinged to spring arms 13 and 14, respectively and with the wings urged toward the contracted positions with a spring 15. 35

In this design the wings are formed, as illustrated in Figs. 3 and 4 with upwardly extended intermediate sections and with the arms 13 and 14 hinged to the intermediate sections of the wings by bearing elements 16 and 17, respectively.

The inner edge of the wing 11 is provided with hook elements 18 which extend through eyes 19 threaded into the body 10 and the wing 12 is provided with similar hook elements 20 that extend through eyes 21 threaded in the opposite side of the body.

The spring 15 extends through an opening 21' in the body 10 and the ends of the spring are secured to the wings 11 and 12 with eye bolts 22 and 23, respectively.

50 The inner ends of the wings are provided with slots 24 and 25 through which the spring 15 extends, particularly as illustrated in Fig. 4 and as the arms 13 and 14 are pressed together to the position shown in Fig. 4 the ends of the spring 15 bend upwardly.

55 The ends of the arms 13 and 14 are provided with upset sections 26 and 27 and similar parts 28 and 29 are provided on the arms at the inner ends of the bearing elements whereby the wings are retained in position on the arms.

60 In the design illustrated in Fig. 5 a body 30 is provided with wings 31 and 32 and the wings are pivotally mounted in the body with pins 33 and 34, respectively. The pins extend through extensions at the sides of the wings and springs 35 and 36 which extend around the pins are positioned in recesses 37 and 38, respectively in the ends of the wings.

65 The ends 39 and 40 of the springs bear against the upper surfaces of the wings and ends 41 and 42 bear against the upper surface of the body whereby the springs urge the wings downwardly.

70 The wings 31 and 32, of this design are hinged to spring arms 43 and 44, similar to the arms 13 and 14 with hinge

elements 45 and 46, respectively. It will be understood, however, that the wings may be hinged to spring actuated elements of other suitable designs.

In the design illustrated in Figs. 7 and 8 wings 47 and 48 are connected to a body 49 with a flat spring 50 which extends through an opening 51 in the body and which is provided with upwardly extended ends 52 and 53 on which the wings are mounted. The wings of this design are also hinged to spring arms 55 and 56, similar to the spring arms 13 and 14, with bearing elements 57 and 58, respectively.

In the design illustrated in Figs. 9 to 13, inclusive a body 60 having wings 61 and 62 mounted on the sides thereof with hinges 63 and 64 is mounted on a bar 65 and the wings are hinged to spring arms 66 and 67.

The arms 66 and 67 are mounted in sockets 68 and 69, respectively on the end of a handle 70 and the bar 65 is mounted in a socket 71 on the end of the handle 72. The handle 72 is attached to the handle 70 with a U-shaped spring 73, one arm of which is secured to the handle 70 with rivets 74 and the other to the handle 72 with rivets 75. As illustrated in the drawings the arms 66 and 67 and the bar 65 are secured to the handles by welding, however, it will be understood that these parts may be connected by other suitable means. The arms 66 and 67 are connected to the wings 61 and 62, respectively by hinged elements 76 and 77.

With the parts arranged in this manner the handles 70 and 72 are drawn together by the thumb and forefinger of a hand with the wings moving upwardly and the body of the bird downwardly, as shown in Fig. 11. It will be understood that the spring 73 may be formed to urge the handles 70 and 72 apart or together, as may be desired.

In the design illustrated in Fig. 14 spring arms 78 and 79 are crimped in ears 80 and 81 on the ends of an arm 82 of a spring element 83 and a bar 84, similar to the bar 65, and upon which the body of the animal may be mounted, extends from the end of a lower arm 86 to which the bar 84 may be secured by crimping, as indicated at the point 87, or by other means. With the body of the bird mounted on the bar 84 the arms 78 and 79 are hinged to the wings, similar to the arms 66 and 67 of the design shown in Figs. 9 to 13.

With the wings hinged to the body, in this manner and with the wings actuated by spring arms as illustrated in the different designs the bird is manually activated by compressing and releasing the spring elements.

It will be understood that other modifications, within the scope of the appended claims, may be made in the design and arrangement of the parts without departing from the spirit of the invention.

What is claimed is:

1. An activated toy comprising a body having a head on one end and a tail extended from the opposite end, wings hinged to the body, a U-shaped spring having arms, 5 means hinging the wings of the body to the arms of the spring, said body having a transversely disposed opening extended therethrough and a spring extended through the opening in the body connecting said wings.

2. An activated toy comprising a body having a head on one end and a tail extended from the opposite end, wings hinged to the sides of the body, a U-shaped spring having arms, said spring positioned with one of said arms extended from the body and with elements of the other of said arms hinged to the wings of the body.

3. In a manually activated toy, the combination which comprises a body in the form of the body of a bird, wings hinged to the sides of the body, said body having a transversely disposed opening extended therethrough, a spring extended through the opening of the body, means 20 attaching the ends of the spring to the wings extended from the body, a U-shaped spring element having arms, and means hinging the wings of the body to said arms.

4. In a manually activated toy, the combination which comprises a U-shaped spring element having arms, a body representing the body of a bird mounted on one of said arms, wings hinged to the sides of the body, spaced spring members extended from the other arm of said spring member and means hinging said spaced spring members to the wings hinged to the body.

5. An activated toy comprising a body having a head on one end and a tail extended from the opposite end, a handle, a bar connecting the body to the handle, wings hinged to the sides of the body, the axis of the hinges being longitudinally disposed whereby the wings are 35 adapted to swing in a transversely disposed vertically positioned plane, spring arms mounted on the handle spaced from the body and parallel to a plane extended longitudinally through the center of the body, and means pivotally connecting the extended ends of the spring arms 40 to the wings whereby the wings are adapted to be actuated by the spring arms.
